UNITED STATES PATENT OFFICE.

JACOB A. SOMMERS, OF COLUMBUS, OHIO.

OVERALLS.

No. 872,089.

Specification of Letters Patent.

Patented Nov. 26, 1907.

Application filed August 22, 1907. Serial No. 389,617.

To all whom it may concern:

Be it known that I, JACOB A. SOMMERS, citizen of the United States, residing at Columbus, in the county of Franklin and State of Ohio, have invented certain new and useful Improvements in Overalls, of which the following is a specification.

My invention relates to the improvement of overalls and the object of my invention is 10 to provide overalls with an improved arrangement of back and front extensions which may be readily attached to or detached from the waist-band. This object I accomplish in the manner illustrated in the 15 accompanying drawing, in which:

Figure 1 is a view in perspective of the upper portion of a pair of overalls looking toward the rear side thereof and showing my improved back and front extensions in place 20 thereon, Fig. 2 is a detail view in elevation of the detached back extension, and, Fig. 3 is a front view of the upper portion of a pair of overalls showing my improved front extension or bib partially disconnected therefrom.

25 Similar numerals refer to similar parts throughout the several views.

1 represents a portion of a pair of overalls which may be of the ordinary or well known make or construction.

30 2 represents my back extension with which is integrally formed diverging shoulder straps.

3. As indicated in the drawing, the rear or body portion of the back extension, flares to-

ward its lower end and is provided in its 35 wider portion with button holes which are indicated at 4, these button holes being de-

signed to be engaged with correspondingly arranged buttons 5 sewed or otherwise se- 40 cured to the waist-band of the garment on the rear side of the latter. From the upper portion of the back extension body 2 lead

the diverging shoulder straps 3 which, as shown, taper toward their lower ends and are provided with suitable button engaging 45 terminations which are indicated at 6.

7 represents an overall front extension which as prescribed for the rear extension, is provided in its lower and wider portion with button holes 8 which are adapted to detach- 50 ably engage buttons 9 sewed or otherwise

secured to the waist-band at the forward side of the garment. The upper end portion of the bib or front extension 7 is provided with buttons 10 which are arranged adjacent to the opposite edges of the bib and which 55 are adapted to be detachably engaged by the terminal devices 6 of the shoulder straps 3. It is obvious that when this front extension or bib is not employed, the engaging devices may be connected with the buttons at the 60 front of the overalls.

Heretofore it has been common for manufacturers to produce and market overalls having permanent back extensions and bibs, these rear extensions being known to the 65 trade as "high backs", and the fact that there is a demand for overalls constructed both with and without the "high backs" and bibs necessitated the manufacture or the handling by dealers of both classes of gar- 70 ments. By my invention it will be readily seen that both the back extensions and bibs may be formed independently of the overalls and that in view of the fact that these extensions are readily attached to or de- 75 tached from the waist-band of the garment, dealers will be able to carry a line of the back and front extensions separate from the overalls, thus admitting of their customers pur- 80 chasing said overalls either with or without these extensions, and obviating the neces- sity of the overalls being manufactured in the different forms.

While I have described buttons as a means of connecting the back extension and bib 85 with the overalls, it is obvious that other suitable and well known fastening devices may be employed. It will be observed that the central button 9, will be utilized for both attaching the bib and closing the fly of the 90 garment.

What I claim, is:

In an attachment for overalls, the combi- 95 nation with a pair of overalls having attach- ing devices arranged at the back and at the front of the waist-band thereof, of a back extension comprising a solid body portion and cut to form integral straps adapted to pass over the shoulders of the wearer, said straps having engaging means at their ends, 100

means for securing the solid back portion to
the fastening devices at the rear of the waist-
band, a detachable bib adapted to engage the
fastening devices at the front of the waist-
band, and members located at the upper
5 edge of said bib and adapted to engage the en-
gaging members of the straps.

In testimony whereof I affix my signature
in presence of two witnesses.

JACOB A. SOMMERS.
